UNITED STATES PATENT OFFICE.

ANDREW L. RIKER, OF NEW YORK, N. Y.

SECTIONAL STEAM-BOILER.

SPECIFICATION forming part of Letters Patent No. 379,725, dated March 20, 1888.

Application filed November 29, 1887. Serial No. 256,454. (No model.)

To all whom it may concern:

Be it known that I, ANDREW L. RIKER, of New York city, in the county and State of New York, have invented a new and useful Improvement 5 in Sectional Steam-Boilers, which improvement is fully set forth in the following specification.

This invention has reference to the construction of sectional boilers or steam-generators, 10 and its object is to realize high efficiency in proportion to the size of boiler, to secure great strength and consequently diminish the liability of explosion, and to produce a boiler which can be easily constructed and put together and 15 at comparatively small cost.

According to this invention each section of the boiler is built up of a number of short lengths of straight pipe and elbows forming a square or rectangular coil, the convolutions of 20 which lie all in the same plane. Each section communicates with the one next above and below at its center and outer end, respectively. This construction gives great compactness and strength. It is cheap, because only short 25 straight lengths of pipe are used, and for the same reason the boiler can be easily built up in any place or removed when necessary.

I am aware that boilers have heretofore been commonly constructed of straight lengths as 30 well as of coils of pipe, and that these have been carried back and forth through and around the fire-space in various ways. The particular construction described, however, is believed to be new, and it possesses the advantages pointed out.

The bottom section of the boiler communicates with a rectangular coil, which surrounds the four sides of the fire-pot, leaving only a suitable opening in front for admitting fuel. 40 This coil is likewise made up of straight lengths with elbows and return-bends. Four separators are employed, and these are in the form of upright tubes or columns, and are placed at the four corners of the structure. Much greater 45 strength results from the employment of four separators instead of a single separator of four times the capacity. The separators are cross-connected at the top by a steam-cross, and the latter communicates with the superheater, 50 from which the steam is drawn as required.

In the accompanying drawings, which form a part of this specification, I have illustrated a steam-boiler constructed in accordance with the invention, Figure I being a side elevation with the outer casing removed; Fig. II, a similar front elevation; Fig. III, a section on line III, Fig. II; Fig. IV, a plan showing the steam-cross and discharge pipes; and Fig. V, a central vertical section on line V, Figs. I and III, looking in the direction of the arrows. 55

The entire boiler is inclosed in a casing, A, which may be of sheet metal, provided at the top with a flue or chimney, B.

The boiler comprises a number of sections, c, d, e, f, g, h, and h', arranged horizontally one 60 above the other. The construction of the sections is best shown in Fig. III. Each section is a rectangular coil composed of short lengths of straight pipe 2, connected at the corners by elbows 3, forming a continuous passage for the 65 water from the inner to the outer end, or vice versa, as the case may be. The inner end, 4, of the section h' communicates with the inner end of the section, h, next above it by a vertical pipe, 25. Section g is identical in construction with section h'. Its outer end is connected with the outer end of section g by elbow 30, and so on through the series. To the inner end of the top section, c, is attached the feed-pipe 8, by which water is supplied to the 70 boiler. After passing through the bottom section, h, the water goes through the rectangular coil i, being connected therewith by the pipe 9, Fig. III. The coil i incloses the fire-pot, as clearly shown in the drawings. It runs 75 partly across the front thereof, Fig. II, then back by return-bend to and entirely around the furnace to the front side again, and back by return-bend 11. Sufficient distance is left between the ends 10 and 11 to permit access to 80 the fire. The last end of coil is connected by the vertical pipe 12 and horizontal pipe 13 with the cross k. The latter consists of four 85 branch pipes radiating from a common central joint, 15, to which the inlet-pipe 13 is connected. The shape of the cross is exactly the same as that of the cross l, Fig. IV, which overlies it. The ends of the pipes k are connected by elbows with vertical pipes 16, which 90 pass down into the upright tubular separators 95 50 from which the steam is drawn as required. 100

D. The latter (four in number) are placed at the four corners of the structure, and are screwed onto pedestals 17, securely bolted to the floor or bed-plate. To the top of the separators are connected the ends of the cross *l*, which, to distinguish it from the water-cross *k*, may be termed the "steam-cross." The central joint or union coupling, 19, of the latter is connected with the superheater *m*, from which steam is drawn as required through steam-pipe 20. The superheater is constructed in the same manner as the boiler-sections.

The water and wet steam from the boiler pass to the separators D by pipes *k* and 16 and the liquid falls to the bottom thereof, the steam passing off by pipes *l*. The four separators D are also connected at the bottom by pipes 22, to which is connected a discharge-pipe, 23. One of the separators D has a gage, 25, to show the level of the water therein, which of course is the same in all, and when this level rises higher than desirable the water can be drawn off through pipes 22 23.

At the top of the fire-chamber is suspended a conical deflector, 26, in order to spread the heat through the various pipes.

It will be noted that while the structure is one of great stability there is perfect freedom for expansion and contraction of the pipes constituting the boiler, the latter being in effect a single continuous pipe free throughout its entire length, and unattached to any fixed point.

It is obvious that modifications can be made in details of construction without departing from the spirit of the invention.

Having now fully described my said invention and the manner of carrying the same into effect, what I claim is—

1. A steam boiler or generator comprising a series of sections, each section composed of straight lengths of pipe and elbows assembled to form an angular coil, the convolutions of which all lie in the same horizontal plane, substantially as described. 40

2. A steam boiler or generator comprising a series of horizontal sections, one above the other, each section composed of straight lengths of pipe and elbows assembled to form a rectangular coil, the successive sections being connected together alternately at their centers and outer ends, substantially as described. 45

3. In a steam boiler or generator, the combination, with the series of horizontal sections placed above the fire-pot, and consisting each of a rectangular coil, of the coil surrounding said fire-pot and consisting of straight lengths of pipe connected by elbows at the corners, substantially as described. 55

4. The combination, with the boiler-sections, of two or more separators, a pipe leading from the boiler and branching to the several separators, and a steam-pipe also branching to the several separators, substantially as described. 60

5. The combination, with the boiler-sections, of the four separators, one at each corner of the boiler, the water-cross, and the steam-cross connected with said separators, substantially as described. 65

In testimony whereof I have signed this specification in the presence of two subscriving witnesses.

ANDREW L. RIKER.
